CLAIM

The ornamental design for a transport tray for ampoule parts, as shown and described.

DESCRIPTION

FIG. 1 is a top perspective view of a transport tray for ampoule parts, showing my new design;

FIG. 2 is a bottom perspective view thereof;

FIG. 3 is a top plan view thereof;

FIG. 4 is a bottom plan view thereof;

FIG. 5 is a side elevational view thereof, the opposite side thereof is identical thereto; and,

FIG. 6 is a front elevational view thereof, the opposite side thereof is identical thereto.
